UNITED STATES PATENT OFFICE.

ZACHARY T. RUSSELL, OF HATTIESBURG, MISSISSIPPI.

ROTARY ENGINE.

1,160,450.

Specification of Letters Patent. Patented Nov. 16, 1915.

Application filed December 12, 1912. Serial No. 736,438.

To all whom it may concern:

Be it known that I, ZACHARY T. RUSSELL, a citizen of the United States, residing at Hattiesburg, in the county of Forest and 5 State of Mississippi, have invented a new and useful Rotary Engine, of which the following is a specification.

My invention relates to new and useful improvements in a rotary engine and more 10 particularly to an engine of this type using steam as the propelling power.

The object of the invention is the construction of an engine of this character in which the piston is held in such position as 15 to be readily acted upon by the steam.

A further object is the provision of means for preventing the loss of steam between the stator and rotor.

With the above and other objects in view 20 which will appear as the description proceeds, the invention resides in the combination and arrangement of parts and in the details of construction hereinafter described and claimed, it being understood that 25 changes in the precise embodiment of the invention herein disclosed can be made within the scope of what is claimed without departing from the spirit of the invention.

In the drawings:

30 Figure 1 is a side elevation with parts broken away to more clearly show the invention. Fig. 2 is a vertical section on line A—A of Fig. 1. Fig. 3 is a sectional view on line B—B of Fig. 1. Fig. 4 is a sectional view on line C—C of Fig. 1.

In the drawings, the numeral 1 indicates the stator, having the side plates 2, between which the rotor 3 mounted upon the axle 4 rotates. Fluid is admitted by the pipe 5 40 and exhausted through the pipe 6. A swinging abutment 7 is pivoted in a recess formed in the stator and is held in its operative position by means of a spring 8. A piston 9 is pivoted in a recess formed in the rotor 45 and is engaged on its under side by the spring 10 and on the top by the spring 11. As clearly shown in the drawings, the spring 11 is of greater length and strength than the spring 10 and when the pressure of the fluid 50 is released from the piston the spring 11 will slightly overcome the spring 10 and allow the piston to move out of contact with the stator and thereby save wear on both the piston and stator.

55 As shown in Fig. 4, I have provided the two plates 12 which are secured to the stator

by means of the bolts 13 and these plates prevent side movement of the abutment 7 and provide means for gaining access to the abutment and also fill the space 14 at the 60 point of the abutment to prevent the loss of fluid.

In order to prevent fluid from leaking out from between the stator and rotor I have provided the packing rings 15 which fit in 65 grooves formed in the stator and rotor.

Fig. 3 is taken on the line B—B of Fig. 1 and as shown the piston is of such width as to engage the packing rings 15 and prevent loss of fluid at the piston. 70

While in the drawings I have only shown one piston it will be understood that any number may be used.

It is thought that from the foregoing description the operation will be fully understood. The fluid which is preferably steam is admitted through the pipe 5 and contacts with the abutment, and piston 9, and thereby rotates the rotor 3. The steam is exhausted through the pipe 6 and after the 80 pressure is relieved from the piston the spring 11 is of such strength as to slightly overcome the spring 10 and allow the piston to move away from engagement with the stator. The piston is held in such position until after it passes the abutment when it will be engaged by the steam and the pressure of the steam with the aid of the spring 10 will overcome the spring 11 and forces the piston into tight contact with 90 the stator. 85

Having fully described my invention, what I claim and desire to secure by Letters Patent is:

A rotary engine, including a stator having a rotor chamber with diametrically disposed intake and exhaust ports, a rotor mounted in the chamber, a swinging abutment connected to the stator, a swinging piston carried by the rotor for movement within and beyond the periphery of the rotor, a spring engaging to hold the under side of said piston beyond the periphery of the rotor, and a flat spring attached to the peripheral face of the rotor and having its free end engaging the upper side of the piston, the last spring being of such a strength as to partly overcome the spring engaging the under side of the piston, whereby under running conditions the pressure fluid moves 110 the piston outwardly to engage the periphery of the stator, the upper spring overcom-

ing the under spring when the rotor is not operated by pressure fluid and removing the piston from contact with the periphery of the stator but projected beyond the periphery of the rotor.

5 In testimony that I claim the foregoing

as my own, I have hereto affixed my signature in the presence of two witnesses.

ZACHARY T. RUSSELL.
